UNITED STATES PATENT OFFICE.

MATTHIAS F. KNOX, OF NASHVILLE, TENNESSEE.

WEIGHING-SCALE.

SPECIFICATION forming part of Letters Patent No. 743,089, dated November 3, 1903.

Application filed February 4, 1903. Serial No. 141,807. (No model.)

To all whom it may concern:

Be it known that I, MATTHIAS F. KNOX, a citizen of the United States, residing at Nashville, in the county of Davidson and State of Tennessee, have invented certain new and useful Improvements in Weighing-Scales, of which the following is a specification, reference being had therein to the accompanying drawings.

10 This invention relates to improvements in weighing-scales, and has for its primary object the provision of a scale which will be as compact as possible and highly effective in operation.

15 To this end the invention contemplates operating mechanism comprising lever-connecting instrumentalities which will have the greatest possible length between bearings, whereby the sensitiveness of the parts is correspondingly increased, and also novel connecting means between the said operating mechanism and the beam or panel, whereby the beam or panel will be devoid of projections throughout its entire extent, thereby 25 presenting no obstruction to the shifting of the poise thereover from end to end of the same, besides enlarging the surface area utilized for indicators or computation-figures.

20 To facilitate a clear understanding of the invention, I have illustrated in the accompanying drawings, forming part hereof, preferable embodiments of the invention, and the novel details in the construction and arrangement of the several parts of the same will be 35 apparent upon an inspection of the detailed description hereinafter when read in connection with said drawings.

30 In the embodiments disclosed an angle-lever interpositioned between the scale pan or platform rod and the lower innermost corner of the beam is utilized, said lever being pivoted at its elbow to a portion of the scale-frame and the respective arms of the lever being as long as possible consistent with the 45 arrangements shown, whereby the leverage is as great as possible, effecting unusual sensitiveness of the movable operating parts. It will also be seen that a bearing is interposed between the upper end of the scale-standard 50 and the lower bar of the panel or beam frame, so that the said frame may be rotated in a

horizontal direction to any desired position for inspection or to bring to view either the front or reverse sides of the beams or panels.

In the drawings, Figure 1 is an elevation 55 of a scale made according to the present invention. Fig. 2 is an enlarged detail view of the angle-lever and the immediately-associated parts, also the bearing, parts being shown in section. Fig. 3 is a detail edge elevation of the connection between the upper arm of the angle-lever and the lower innermost corner of the beam. Fig. 4 is a section on the line *xx* of Fig. 3. Fig. 5 is an elevation, portions being shown in section, of a second 60 embodiment of the invention, showing a somewhat-modified arrangement. Fig. 6 is a detail thereof. Fig. 7 is a plan view of the platform of the construction shown in Fig. 5, indicating the manner of connecting the angle-lever to said platform. Fig. 8 is a sectional view on the line *77* of Fig. 7. Figs. 9 and 10 are detail views of swivel connections employed in rotary-beam constructions, and Fig. 11 is a detail of a slot-and-pin connection. 75

Referring more specifically to the drawings, wherein like reference characters will refer to corresponding parts in the several views, A designates a scale-base having the usual 80 platform or pan B and hollow upright or standard C at one end thereof, through which passes the connecting-rod D, operatively associated with the platform or pan in any ordinary or desired manner. 85

E denotes the beam or panel portion of the scale, the same being shown in the present instance as comprising a plurality of superposed slightly-separated panels *e*, on both surfaces of which are arranged any desired 90 computation-figures or indicator characters. The edges of the beam are connected to form a unit by cross-bars *e'*, said unit being mounted to swing vertically by pivoting the inner cross-bar at a point centrally located intermediate 95 its ends to the inner vertically-disposed arm F of a beam or panel frame, the opposite parallel arm of which is indicated at F' and the lower connecting portion at F''. The inner cross-bar *e'* projects downwardly and outwardly for a short distance at its lower end, and to this extension is pivotally secured the 100

upper arm G of an enlarged angle-lever, the pivotal connection therebetween comprising a headed pin g, passing through slotted reduced portions g' on the lever-arm and the extension, Fig. 11. The aforesaid angle-lever is pivoted at its elbow at G'' to a lug g'' on the arm F of the panel-frame, and the lower arm G' thereof extends inwardly in a horizontal direction and connects at its end, through the medium of a pivoted link d', with the hooked end d of the rod D. The arm G of the angle-lever supports an adjustable scale-pan weight II, slideable upon the rod h, secured to said arm, while the lower arm G' thereof carries the adjusting-weight II', having a threaded adjustment upon the rod h', connected to an ear h'', depending from said arm G'.

From the foregoing description it will be apparent that by the interposition of the angle-lever between the rod G and the cross-bar of the panel unit the greatest possible distance between the bearings of the operating parts is enabled, thereby obtaining the desirable characteristics incident to the utilization of long levers, notably that of marked sensitiveness.

The bearing upon which the panel-frame may be rotated will now be described. The upper end of the upright or standard is screw-threaded at i for attachment to a corresponding interiorly-threaded portion of a hollow extension I, the same having a shoulder i', arranged to rest upon the upper surface of the standard. The tubular portion i'' passes through a flattened portion f'' of the lower connecting member of the panel-frame and is secured to said flattened portion by means of a nut K and washer k, Fig. 2. At the lower end of the tubular portion i'' the extension I has a projecting rim L, in the upper surface of which is formed a raceway l for the reception of balls l', which constitute the bearing for the panel-frame and upon which said frame may be rotated to any desired position in a horizontal direction. The rod D may be provided with any convenient swivel connection at either its upper or lower end, so as not to interfere with the turning of the beam or panel—for instance, that shown in Figs. 9 and 10.

In the modified construction (illustrated in Figs. 5 and 6) the angle-lever (designated M in this instance) is brought in closer relation to the scale pan or platform B', the same having its lower arm operatively associated with the pan or platform rather than being indirectly associated therewith, as in the other figures, when the connecting-rod D is employed. The connection between the lower arm of the angle-lever in this instance and the pan or platform may be through the medium of any desirable equalizing levers, that shown, Figs. 7 and 8, comprising the V-shaped lever 2 and Y-shaped lever 3, yieldably connected by a pin 5, said levers being secured to the scale

structure at the corners thereof by links 4 and supporting the pan or platform upon knife-edge bearings 7. The lower arm of the angle-lever is linked at 6 to the tailpiece of the Y-shaped lever 3. It is also to be noted that in this modification the angle-lever is inclosed within the base A' and standard C', said lever being pivoted at m at a point approximately the juncture of said base with 75 said upright. To operatively connect the upper end of the angle-lever with the depending extension N of the panel member corresponding to the extension of the connecting cross-bar e' in the preceding description, I provide a link R, having the knife-edges r, said link loosely embracing the ends m' and n of the arm M and extension N and engaging the notches m'' and n' therein. The panel-frame in this instance comprises the bar F'', 80 having the inner upwardly-curved extension F''', to the end of which the panel member is pivoted at f'''. The panel member comprises the beams e e, slideable upon which are the poises O, and the connecting member e'', 90 carrying the stem or projecting portion p', guided in its movement by the vertical portion P' of the panel-frame in the ordinary manner.

In both forms of the invention the poises O 95 are alike, each comprising a member upon the opposite surface of the panel arranged to register with the computation-figures or indicators thereon and top and bottom connecting-plates, the registering members being also 100 provided with pointers or fingers, if desired. While this peculiar construction of poise may possess novel features, I shall not herein claim the same, because it is thought that it should more properly form the subject-matter of a 105 separate application.

To maintain the beam or panel portion of the scale stationary when the instrument is out of service, a catch P is pivoted at p to the end of the arm F', said catch having inwardly-directed fingers p', arranged to be thrown over a similar finger p'' on the outermost cross-bar e' of the panel-section and arranged to extend between the fingers of the catch P.

While the various details of the construction have been specifically defined herein, it is to be understood that it is not my intention to be limited in an interpretation as to the scope of the invention to any such details 120 except in so far as they may be definitely included in the appended claims, because many minor changes and alterations may be made without departing in the least from the spirit of the invention.

Having thus described the invention, what is claimed as new, and desired to be secured by Letters Patent, is—

1. In a weighing-scale, the combination with a standard, a pan and beam, of operating instrumentalities between the pan and beam, 130 including an angle-lever arranged above the

standard one arm of which is operatively associated with the beam and the opposite arm of which is operatively associated with the pan, and a pivot-bearing for said angle-lever; substantially as described.

2. In a weighing-scale, the combination with a pan and beam, of operating instrumentalities therebetween including an angle-lever arranged above the pan one arm of which is operatively associated with the beam and the opposite arm of which is operatively associated with the pan, a pivot for said angle-lever, and an adjusting-weight carried by one arm of the angle-lever; substantially as described.

3. In a weighing-scale, the combination with a pan and beam, of operating instrumentalities therebetween including an angle-lever one arm of which is operatively associated with the beam and the opposite arm of which is operatively associated with the pan, a pivot for said angle-lever, a scale-pan weight carried by said angle-lever, and an auxiliary adjusting-weight also carried by said angle-lever; substantially as described.

4. In a weighing-scale, the combination with a pan and beam, of operating instrumentalities therebetween including an angle-lever one arm of which is operatively associated with the beam and the opposite arm of which is operatively associated with the pan, a pivot for said angle-lever, a scale-pan weight carried by one arm of said angle-lever, and an auxiliary adjusting-weight carried by the other arm of said angle-lever; substantially as described.

5. In a weighing-scale, the combination with a pan and beam, of operating instrumentalities therebetween including an angle-lever one arm of which is operatively associated with the pan, a pivot for said angle-lever, and a pivot connection between the other end of the angle-lever and the beam, said connection comprising adjacent reduced portions on the beam and lever-arm, and a pin passing through said reduced portions; substantially as described.

6. In a weighing-scale, the combination with a pan and beam, of operating instrumentalities therebetween including an angle-lever one arm of which is operatively associated with the pan, a pivot for said angle-lever, and a pivot connection between the other end of the angle-lever and the beam, said connection comprising adjacent slotted reduced portions on the beam and lever-arm, and a pin connecting said reduced portions and entering the slots therein; substantially as described.

7. In a weighing-scale, the combination with a pan and beam, of operating instrumentalities therebetween including an angle-lever one arm of which is operatively associated with the pan, the opposite end of said lever extending in an approximately vertical direction, a pivot for said angle-lever, and a pivotal connection between said opposite end of the

angle-lever and the beam; substantially as described.

8. In a weighing-scale, the combination with a pan and beam, of operating instrumentalities therebetween including an angle-lever one arm of which is approximately horizontally disposed and operatively associated with the pan, the opposite end of said lever being approximately vertically disposed, a pivot for said angle-lever, and a pivotal connection between the vertically-disposed end of the angle-lever and the beam; substantially as described.

9. In a weighing-scale, the combination with a pan and beam, of operating instrumentalities therebetween including an angle-lever one arm of which is operatively associated with the pan, a pivot for said angle-lever, a projecting portion at the edge of the beam, and a pivot connecting said projecting portion directly to the other end of the angle-lever; substantially as described.

10. In a weighing-scale, the combination with a pan and beam, of operating instrumentalities therebetween including an angle-lever one arm of which is operatively associated with the pan, a pivot for said angle-lever, a depending projection at the edge of the beam, and a pivot connecting said depending projection directly to the other end of the angle-lever; substantially as described.

11. In a weighing-scale, the combination with a pan and beam, of operating instrumentalities therebetween including an angle-lever having an approximately vertically disposed arm and an approximately horizontally disposed arm, the horizontal arm of said lever being operatively associated with the pan, a pivot-bearing for said angle-lever, and a movable connection between the vertical arms of the angle-lever and the beam; substantially as described.

12. In a weighing-scale, the combination with a pan and beam, of operating instrumentalities therebetween including an angle-lever one arm of which is operatively associated with the beam, a depending rod the lower portion of said rod being operatively associated with the pan, and means for attaching the upper end of said rod to the opposite arm of the angle-lever; substantially as described.

13. In a weighing-scale, the combination with a pan and beam, of operating instrumentalities therebetween including an angle-lever one arm of which is operatively associated with the pan and the opposite end of which is operatively associated with the beam, a beam-frame comprising a vertically-disposed arm and a lower arm, a pivotal connection between the vertically-disposed arm of the frame and the beam, and a pivotal connection between said vertically-disposed arm and the angle-lever; substantially as described.

14. In a weighing-scale, the combination with a pan and beam, of operating instrumen-

- talities therebetween including an angle-lever one arm of which is operatively associated with the pan, and the opposite end of which is operatively associated with the beam, 5 a beam-frame comprising a vertically-disposed arm and a lower horizontally-disposed arm, and a pivotal connection between said vertically-disposed arm and the angle-lever, substantially as described.
15. In a weighing-scale, the combination with a pan and beam, of operating instrumentalities therebetween including an angle-lever one arm of which is operatively associated with the pan and the opposite end of 15 which is operatively associated with the beam, a beam-frame comprising a vertically-disposed arm and a lower arm, a pivotal connection between the vertically-disposed arm of the frame and the angle-lever, and an adjusting-weight supported from the underside of the lower arm of said lever; substantially as described.
16. In a weighing-scale, the combination with a pivoted beam, operating instrumentalities therefor, and means for retaining the beam in an inactive position comprising a projection thereon, and a catch pivoted to swing laterally of the beam and arranged to coöperate with said projection; substantially 25 as described.
17. In a weighing-scale, the combination with a beam pivotally mounted at one end, operating instrumentalities therefor, and means for retaining the beam in an inactive 25 position comprising a projection on the beam at the end thereof opposite its pivoted end, and a catch pivoted to swing laterally of the beam and arranged to coöperate with said projection; substantially as described.
18. In a weighing-scale, the combination with a pivoted beam, operating instrumentalities therefor, and means for retaining the beam in an inactive position comprising a projection thereon, and a pivoted catch having 45 separated portions arranged to coöperate with the projection on the beam; substantially as described.
19. In a weighing-scale, the combination with a beam pivotally mounted at one end, 50 operating instrumentalities therefor, and means for retaining the beam in an inactive position comprising a projection on the beam at the end thereof opposite its pivoted end, and a pivoted catch having separated projections arranged to coöperate with the projection on the beam or panel; substantially as described.
20. In a weighing-scale, the combination with a pan and beam, of operating instrumentalities therebetween including an angle-lever, and a beam-frame to which the beam and the angle-lever are pivoted, one arm of said angle-lever being operatively associated with the beam and the opposite arm being operatively associated with the pan.
21. In a weighing-scale, the combination with a pan and pivoted beam, of a support 55 for said pivoted beam, and operating instrumentalities between said pan and beam including an angle-lever pivoted to the beam-support, one arm of said angle-lever being operatively associated with one end of said beam and the opposite arm being operatively associated with the pan. 70
22. In a weighing-scale, the combination with a pan and beam, of operating instrumentalities therebetween including a pivoted angle-lever having one arm projecting upwardly relative to the pan and operatively associated with the beam, and another arm operatively associated with the pan. 75
23. In a weighing-scale, the combination with a pan and beam, of a beam-frame having a vertically-disposed arm and a lower arm, and operating instrumentalities between the pan and beam including a pivoted angle-lever arranged within the beam-frame, one arm of said lever being operatively associated with the beam and the opposite arm thereof being operatively associated with the pan. 85 90
24. In a weighing-scale, the combination with a pan and beam, of a beam-frame having a vertically-disposed arm and a lower arm, and operating instrumentalities between the pan and beam including an angle-lever arranged within the beam-frame, one arm of said lever being operatively associated with the beam, a depending rod operatively associated with the pan, and a movable connection between the upper portion of said depending rod and the other arm of the angle-lever. 95
25. In a weighing-scale, the combination with a pan and beam, of a beam-frame having a vertically-disposed arm and a lower arm, and operating instrumentalities between the pan and beam including an angle-lever arranged within the beam-frame, one arm of said lever being operatively associated with the beam, a depending rod operatively associated with the pan, a movable connection between the upper portion of said depending rod and the other arm of the angle-lever, and an adjusting-weight carried by the angle-lever. 105 110 115
26. In a weighing-scale, the combination with a pan and beam, of operating instrumentalities therebetween including an angle-lever arranged with one arm thereof extending longitudinally of the beam, and means connecting the other arm to said beam. 120
27. In a weighing-scale, the combination with a pan and beam, of operating instrumentalities therebetween including an angle-lever arranged with one arm thereof extending longitudinally of and beneath the beam, and means connecting the other arm to said beam. 125
28. In a weighing-scale, the combination with a pan and beam, of operating instrumentalities therebetween including an angle-lever arranged within approximately the same vertical plane as the beam, said lever having a vertically-disposed arm connected to said beam. 130

29. In a weighing-scale, the combination with a pan and beam, of operating instrumentalities therebetween including an angle-lever arranged within approximately the same vertical plane as the beam and beneath said beam, said lever having a vertically-disposed arm connected to said beam.

In testimony whereof I affix my signature in presence of two witnesses.
